UNITED STATES PATENT OFFICE.

DAVID MILES HAYWORTH AND ELBERT VICTOR PUTNAM, OF CHICAGO, ILLINOIS.

CUSPIDOR.

1,075,297.

Specification of Letters Patent.

Patented Oct. 7, 1913.

Application filed January 22, 1910. Serial No. 559,631.

To all whom it may concern:

Be it known that we, DAVID MILES HAYWORTH and ELBERT VICTOR PUTNAM, citizens of the United States, residing at Chicago, in the county of Cook and State of Illinois, have invented certain new and useful Improvements in Cuspidors, of which the following is a specification.

This invention relates to certain new and useful improvements in cuspidors for use in railway cars, although designed for use in other places.

The present invention has for its objects among others to provide a simple yet efficient and durable sanitary cuspidor readily applied, requiring practically no attention, and the parts so arranged and assembled as not to be liable to get out of order, but on the other hand most reliable and positive in their action.

We mount the cuspidor on a movable support, normally raised into a vertical position and serving as a closure for the opening in which the cuspidor is retained when not in use, and within the chamber to which access is had through this opening is disposed a device for washing the cuspidor, said washing device being controlled by the opening and closing of said movable support by which the cuspidor is carried.

Other objects and advantages of the invention will hereinafter appear, and the novel features thereof will be specifically defined by the appended claims.

The invention, in its preferred form, is clearly illustrated in the accompanying drawings, which, with the numerals of reference marked thereon, form a part of this specification, and in which—

Figure 1 is a front elevation showing the cuspidor in its position for use. Fig. 2 is a vertical section with the cuspidor and its movable support in elevation. Fig. 3 is a perspective view of the collection receptacle removed. Fig. 4 is a view partly in section, looking down upon the collection receptacle in place. Fig. 5 is a view of the movable support carrying the cuspidor. Fig. 6 is an enlarged sectional view, with parts in elevation, showing the washing apparatus and its controlling rod, etc.

Like numerals of reference indicate like parts throughout the several views.

Referring to the drawings 1 designates a vertical wall, it may be of a railway car, or

a house, or any other place, in which is an opening 2.

3 is a door or movable support hinged at one edge as at 4 to the vertical wall 1, as seen clearly in Figs. 1 and 2, a spring 5 being shown for the purpose of holding the door or movable support in its vertical position. 6 is a cuspidor of any well known or preferred form of construction secured to this door or movable support in any well known way, in this instance shown as held by clips or the like 7 shown in Fig. 5.

8 is a wall or vertical support parallel with the wall 1 as seen in Fig. 2, and in the space 9 between the said walls is supported a receptacle 10 in this instance shown in Fig. 2 as provided at its upper edge with a flange 11, see also Fig. 5, which flange is supported upon the ledge 12 of a plate or support 13 secured within the space 9 in any suitable manner.

In some instances we may employ a curved guard 18 as seen in position in Fig. 4.

Within the space 9 depends a water pipe 19 connected with any suitable source of water supply and to the lower end of this pipe is connected a downwardly inclined pipe 20 carrying at its free end a sprinkler or rose 21.

At the junction of the pipe 19 and the inclined portion 20 is disposed a valve 22, the stem 23 of which has connected therewith an arm 24 the free end of which is provided with an elongated slot 25.

26 is a rod having one end connected with this arm by means of a projection or pin 27 working in said slot as seen clearly in Fig. 6. The other end of this rod 26 carries a disk or plunger 28 which is adapted to fit snugly within a cup 29 secured in any suitable manner in proper position on the inner or normally upper face of the movable support 3 as seen clearly in Fig. 2.

30 is a spring connected at one end to the end of the rod 26 at its junction with the arm 24, the other end of this spring being disposed within a socket or chamber 31 in the wall 8 as seen best in Fig. 6.

The door or movable support 3 may be provided with a knob or ring or the like 32 as seen in Fig. 2 by which it may be manipulated when desired.

With the parts constructed and arranged substantially as hereinbefore described the operation will be readily understood espe-

cially when taken in connection with the annexed drawings. In the position in which it is seen in Fig. 2 the cuspidor is ready for use. After use, the movable support 3 is drawn up into vertical position when it closely fits the opening 2 and closes the same. As the door is closed the cup 29 engages the plunger 28 and pushing thereon turns the valve 22 and turns on the water in the pipe 19 and the water flowing out through the rose 21 serves to thoroughly wash and cleanse the cuspidor, which is then in the position seen by dotted lines in Fig. 2. The material, as it is washed out of the cuspidor, falls in to the receptacle 10 from whence it can be easily removed when desired. When the movable support 3 is again brought into its horizontal position the spring returns the arm 24 to its former position, turning the valve so as to shut off the water.

Modifications in detail may be resorted to without departing from the spirit of the invention or sacrificing any of its advantages.

What is claimed as new is:—

1. The described device consisting of a casing having an opening thereinto, a removable receptacle, a spring controlled door for said opening, a cuspidor on said door, a spray pipe in said casing, a valve therein, a piston rod connected to said valve, a piston on the free end thereof, and a piston cylinder on said door adapted to engage said piston.

2. The described device consisting of a casing having an opening thereinto, a removable receptacle, a spring controlled door for said opening, a cuspidor on said door, a spray pipe in said casing, a valve therein, a piston rod connected to said valve, a piston on the free end thereof, and a piston cylinder on said door adapted to engage said piston, said rod adapted to operate said valve, a valve stem connecting said valve and said rod, said stem being spring controlled.

3. The described device consisting of a casing having an opening thereinto, a removable receptacle, a spring controlled door for said opening, a cuspidor on said door,

a spray pipe in said casing, a valve therein, a piston rod connected to said valve, a piston on the free end thereof, and a piston cylinder on said door adapted to engage 55 said piston, said rod adapted to operate said valve, a valve stem connecting said valve and said rod, said stem being spring controlled, said rod having sliding movement on said stem.

4. A device of the kind described comprising a casing having an opening, a door in said opening movable to a horizontal position, a spring mounted on the outer wall of the casing and normally holding 65 said door shut, a water supply pipe mounted on the back wall of said casing and having a forwardly inclined jet offset, a bowl on said door movable within range of said offset, a valve in said offset, an arm carried 70 by said valve exteriorly of said offset and having an upper elongated slot, a rod pinned in the slot of said arm and having a disk at its free end, said back wall formed with a socket, a horizontally disposed cup 75 on said door, and a spring in said socket engaging said rod to hold its disk in the path of movement of said cup when the door is closed, said cup engaging the disk to cause said arm to open said valve.

5. The described device consisting of a casing, having an opening thereinto, a receptacle, a spring controlled door for said opening, a cuspidor on said door, a spray pipe in said casing, a valve therein, a rod 85 connected to said valve, means for supporting the free end of said rod, a valve stem connecting said valve and said rod, said stem being spring controlled and a guard for said receptacle.

In testimony whereof we affix our signatures, in presence of two witnesses.
